(57) **CLAIM**

The ornamental design for a ten-chambered flexible ammunition packaging as shown and described.

DESCRIPTION

FIG. 1 is a front perspective view of a ten-chambered flexible ammunition packaging according to the present invention.

FIG. 2 is a front elevation view of the ten-chambered flexible ammunition packaging illustrated in FIG. 1. The rear view of the ten-chambered flexible ammunition packaging is a mirror image of the front view.

FIG. 3 is a top plan view of the ten-chambered flexible ammunition packaging illustrated in FIG. 1.

FIG. 4 is a bottom plan view of the ten-chambered flexible ammunition packaging illustrated in FIG. 1; and,

FIG. 5 is a left side elevation view of the ten-chambered flexible ammunition packaging illustrated in FIG. 1. The right side elevation view of the ten-chambered flexible ammunition packaging is identical to the left side elevation view.
